CLAIM

The ornamental design for a golf cart cover, as shown and described.

DESCRIPTION

FIG. 1 is a front, left, and top perspective view of a golf cart cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising a buckle; and,

FIG. 9 is a partial enlarged view of an area labeled 9 in FIG. 1 comprising a zipper head.

The broken lines shown in the drawings are included for the purpose of illustrating portions of the golf cart cover that form no part of the claimed design.

The dash-dash broken lines illustrate portions of the golf cart cover which form no part of the claimed design. The long dash-short dash broken lines depict the boundaries of the partial enlarged views and form no part of the claimed design. The long dash-short dash broken lines indicating the detail views in FIG. 1 show lead lines and form no part of the claimed design.
